UNITED STATES PATENT OFFICE.

EMILE PHILIPPART, OF LIEGE, BELGIUM.

AUTOMATIC PISTOL.

Application filed August 10, 1926. Serial No. 128,388.

The present invention relates to that type of automatic pistols in which the cartridge magazine is pivotably disposed within the handle of the pistol, thereby being capable 5 to transmit the pressure necessary for releasing the cocked hammer, to the hammer arresting mechanism. It is known that in weapons of this type the whole mechanism assumes a safety position when the magazine 10 is drawn out from the handle, this being evident in view of the fact, that in such case there will be no member capable of transmitting the trigger pressure to the hammer arresting mechanism.

Moreover it is evident that in the pistols in question the magazine may serve itself as a trigger.

The object of the present invention is an improvement in automatic pistols of the 20 type mentioned above.

The annexed drawing Figure 1 represents by way of example one embodiment of the invention partly in section. Figure 2 represents a detail:

1 is the body of the pistol, forming the handle at 2, and provided with the barrel 3 and the breech-slide 4, which latter contains the firing pin 5. Within the rear part of the handle 2 is removably disposed 30 in any usual manner, for instance by the intermediary of the safety bolt 6 and of a pin 7, a piece 8 capable to pivot rearwardly around the pin 7 and supporting the hammer 9 and the hammer actuating mechanism.

The handle 2 contains moreover a magazine 10, capable of pivoting within said handle in the known manner, that is to say, around an axis passing through the point 40 11, and in the senses of the arrows 12 and 13, the angular displacement of the magazine in the sense of arrow 12 being obtained by manual pressure, whereas its angular displacement in the sense of arrow 13 is assured 45 by the action of the magazine catch 14 actuated by a spring 15.

According to the present invention the hammer 9, having its pivot at 16, is actuated by the main spring 17 through the intermediary of a rod 18, which on the one hand, is guided at its interior extremity in a suitably 50 perforated projection 19 of the piece 8, and which on the other hand, is articulated to the hammer 9 at a point 20, which latter is situated, at the cocked position of the hammer (that shown in the drawing) at the left

hand side of the plan xy passing through the hammer pivot 16 and through the center of the guiding hole within the projection 19. The corresponding axial plan of the rod 18 60 has been represented by the line wz . Thus, it is obvious that in the cocked position of the hammer, the compressed main spring tends to provoke a rotation of the hammer, in a clockwise direction, such clockwise displacement of the hammer being limited by the shoulder 21 of piece 8, serving as an abutment for the projection 22 of the hammer. Thus the hammer will be maintained in the cocked position by the pressure of the main 70 spring.

The hammer 9 is moreover provided with a shoulder 23, forming a suitable face at 24. On the other hand the main body 1 of the pistol is cut away on both sides at 25, thereby 75 permitting a pressure to be exerted directly upon the front face 26 of the cartridge magazine.

As soon as the breech slide 4 has assumed its closed position it will be sufficient to 80 exert a pressure upon the front face 26 of the cartridge magazine.

This latter will transmit the pressure to the shoulder 23 of the hammer, thereby angularly displacing this latter in an anticlockwise direction. As soon as the point of articulation 20 of the rod 8 to the hammer 9 passes from the left to the right of the line xy , the pressure of the main spring 17 causes the hammer 9 to execute its blow 90 against the firing pin 5.

The lower extremity of the main spring 17 may press against the projection 19 of part 8 through the intermediary of a washer or annular plate 27 seated upon a spherical or 95 equivalent perforated piece 28 supported by the projection 19.

It is evident that the seat of the lower extremity of the main spring may be as well constructed as shown in Figure 2 which 100 needs no further explanation.

As mentioned above the shoulder 23 of the hammer forms a suitable face or edge 24. The destination of this latter is the following: when the hammer is in a cocked position and the magazine is introduced in the handle of the pistol it may occur that the right hand upper edge of the magazine comes into contact with the hammer, such contact being capable of producing the involuntary 105 liberation of the hammer. Now the face 24 is disposed in such a manner, that any pres-

sure exerted by the magazine in the circumstances mentioned above upon the hammer, will only impede the liberation of the latter.

What I do claim and desire to secure by 5 Letters Patent is:

1. In an automatic pistol having a pivotally disposed cartridge magazine through the intermediary of which the hand pressure is communicated to the hammer locking 10 mechanism, thereby provoking the liberation and the blow of the hammer, the handle of the pistol being for this purpose suitably cut away at the front of the magazine, a hammer pivoted within the handle part of 15 the pistol, a suitably perforated projection upon said handle part, a rod suitably guided by one of its extremities within said perforated projection, and articulated by its other extremity to the hammer at a point, which 20 at the cocked position of the hammer is disposed at one side for instance in front of the line passing through the pivot center of the hammer and through the center of the hole within said projection, this cocked position 25 being determined through the contact be-
tween the suitably formed hammer head and

a shoulder of said handle part a spring combined with said rod and pressing on the one hand against said projection of said handle part and on the other hand through the intermediary of said rod against the hammer at said point, thereby maintaining the hammer in the cocked position, and a shoulder upon said hammer serving to transmit the angular displacement of the magazine to the 30 hammer, the displacement of the latter causing the said point of articulation to move from the one side of said line to its other side thus provoking the blow of the hammer.

2. Automatic pistol according to claim 1, 40 characterized by the fact that the lower portion of said shoulder of the hammer is profiled in such a manner, as to obviate the liberation of the cocked hammer through the upper corresponding part of the magazine, 45 during the introduction of this latter within the handle of the pistol.

In testimony whereof, I have signed my name to this specification at Antwerp, Belgium this 16th day of July, 1926.

EMILE PHILIPPART.
